UNITED STATES PATENT OFFICE.

CLARENCE P. COOK, OF WATERBURY, CONNECTICUT, ASSIGNOR TO SCOVILL MANUFACTURING COMPANY, OF WATERBURY, CONNECTICUT, A CORPORATION OF CONNECTICUT.

COMBINED MATCH BOX AND COIN HOLDER.

Application filed December 2, 1924. Serial No. 753,422.

This invention relates to certain improvements in a combined match box and coin holder.

It is the especial object of the invention 5 to produce a box of such a size as may be readily carried in the pocket of the user which will be provided with a compartment for carrying matches, as, for instance, a bunch of paper matches having a striking 10 surface, and a compartment for the reception of coins, carfare tokens and the like, the box being provided with a cover so arranged that a match may be struck without opening the cover, the cover acting to close 15 the coin compartment of the box.

It is a further object of the invention to provide a box of this character of improved construction which can be cheaply made, which will be durable and which will carry 20 for ready access the desired number of coins or tokens.

With these and other objects not specifically referred to in view, the invention consists in certain novel parts, arrangements 25 and combinations which will be described in connection with the accompanying drawings to show one embodiment of the invention, and the novel features will be pointed out in the claims hereunto annexed.

Referring now to these drawings,—

Figure 1 is a perspective view of the improved box with the cover open;

Figure 2 is a sectional view of the same, a bundle of matches, such as a card of paper 35 matches, being shown in this figure.

Figure 3 is a detail sectional view, on an enlarged scale, of the coin end of the box, the view being taken on line 3—3 of Fig. 1.

Figure 4 is a sectional view taken on line 40 4—4 of Fig. 3, and

Figure 5 is a perspective view of the partition and coin holders.

Referring now to these drawings, the box includes a bottom 1, side walls 2, 3 and end 45 walls 4, 5, these parts being preferably formed from a single blank of suitable material, as light metal. The box is, as indicated at 6, deeper at one end than at the other, the side walls 2, 3 shown as sloping back- 50 wardly to form the shallow end 7. As shown, the back wall 5 is turned inwardly for a short distance, as indicated at 5' in Fig. 2. Between the ends 6 and 7 is hinged a cover 8, this cover being hinged on a pin

9 supported in ears 10 formed on the upper 55 edges of the side walls. This cover, it will be observed, does not extend entirely to the inturned edge 5', but a space, indicated at 11, is left between the end 5' and the pin 9, through which a match can be struck on a 60 suitable striking surface.

This box is divided by a partition into a coin holding compartment and a compartment for holding matches or any other desired article, such as a powder compact. 65 Where the compartment is used for matches, these matches may be in packages, as for instance, a card 12 having a striking face 13, the card being inserted in the compartment, indicated at 14, so that the striking surface 70 is exposed through the opening 11 in the box and a match can be struck when the cover is closed, thus avoiding danger of igniting the rest of the match bunch.

In the forward or deep end of the box 75 is located a partition which is provided with means for holding coins, carfare tokens and the like. This partition includes a plate of metal formed to provide a top 15, a back wall 16 which rests on the bottom of the 80 box, a front wall 17 and side flanges 18, the top 15 being a little lower than the side walls of the box and the side flanges. These side flanges are also provided with shallow cut away portions 19, as shown in Fig. 5. 85

This partition is held securely in the box by engaging projections on the side walls of the box. While these projections may be formed in various ways, as shown, the parts are conveniently held together by bending 90 over portions 20 of the side walls of the box so as to engage the inside of the side flanges 18, the top of the bent over portions 20 lying in the recesses 19, as shown in Fig. 1, so as to form a smooth edge.

This partition carries coin holders which, in the construction illustrated, are made separate from the partition plate. As shown, the partition plate is apertured to receive cylindrical members 21 in which are 100 located coin seats 22 which rest on springs 23 bearing on the bottom of the box and against the seats. These seats are in the form of inverted cups and are held in position in the holders by providing the holders with stops, these stops being located at the rear side of the holders so as to permit the insertion and removal of coins, and are con- 105

veniently formed by turning in the top edge of the holders, as indicated at 24.

The holders may be positioned in the partition plate in a convenient manner by forming the holders with a bead 25 which bears against the under surface of the top plate 15, as clearly shown in Figs. 3 and 4.

In assembling the parts, the coin holders are inserted in the plate from beneath, and 10 the partition with the coin holders, their seats and springs are then placed in the box and the edges 20 turned down to hold the parts in position.

The front wall 4 is, as shown, slightly below the front wall 17 of the partition plate so 15 that the coins may be readily slipped out of the box. The cover is provided with a turned over front edge 26 which extends down over the front wall 4 of the box, as shown in Fig. 20 3, and this cover is, or may be, provided with a hole 27 which engages a projection 28 formed on the front wall 4. While this is a convenient way of securing the cover, it will be understood that various other ways can 25 be used if desired.

With the construction shown and described, a very simple and attractive box has been produced for holding matches or other articles and coins in which the coins are held 30 so as to be readily removable from the box, and in which the coin holding parts are easily assembled and positioned in place. While the embodiment of the invention shown is a desirable one, it will be understood 35 that various changes may be made in the specific structure of the parts without departing from the invention as defined in the claims hereunto appended.

What I claim is:

40 1. A new article of manufacture, a metal box having a bottom end and side walls made of a single piece of material, said side walls being deeper at the front than at the back, a partition plate having a top arranged 45 at one end of the box and held in place by projections on the side walls of the box, coin holders arranged side by side widthwise of the box and secured in the partition having

spring seats for holding coins and the like, and a cover pivoted to the side walls of the 50 box at a point intermediate the end walls and having an opening for access to the interior of the box without opening the cover.

2. A new article of manufacture, a shallow metal box having a partition plate at 55 one end thereof, projections on the side of the box engaging with the plate to hold it in position, spring seated holders in the partition arranged widthwise thereof for coins and the like, a compartment for holding an 60 article located behind the partition, and a cover for the box.

3. A new article of manufacture, a shallow box deeper at one end than the other, a partition plate at the deep end of the box provided with side flanges, said plate being held in place by turning a part of the sides of the box over the flanges, spring seated holders for coins or the like in the partition, a compartment for matches behind the partition and a cover for the box.

4. A new article of manufacture a box having a coin holding compartment formed of a partition plate having a back wall seating on the bottom of the box, a top, side flanges projecting above the top and engaging projections on the side walls of the box, coin holders having a part engaging the top of the partition for securing the holders in place, spring coins seats in the holders, and means 75 so on the holders for holding the seats in place.

5. A new article of manufacture, a box having coin holding compartments formed in a partition plate which has a back wall seating on the bottom of the box and dividing the box into two compartments, a top, side flanges projecting above the top and engaging projections on the side walls of the box, a front flange having frictional engagement with the front wall of the box, said front flange being lower than the top, and spring seated holders for coins or the like 85 mounted in the partition.

In testimony whereof, I have hereunto set my hand.

CLARENCE P. COOK.
